Primary Examiner — Rashida C. Walshon*(74) Attorney, Agent, or Firm* — Marshall A. Lerner; Steven J. Kim; KLEINBERG & LERNER, LLP(57) **CLAIM**

The ornamental design for a heel component as shown and described.

DESCRIPTION

FIG. 1 is a front perspective view of a heel component in accordance with my new design;

FIG. 2 is a left side view thereof;

FIG. 3 is a right side view thereof;

FIG. 4 is a front view thereof;

FIG. 5 is a rear view thereof;

FIG. 6 is a top plan view thereof;

FIG. 7 is a bottom plan view thereof;

FIG. 8 is a bottom perspective view thereof; and,

FIG. 9 is a rear perspective view thereof.

The dashed broken lines define portions of the upper, midsole, and outsole that form no part of the claimed design.

1 Claim, 8 Drawing Sheets(56)
